(57) **CLAIM**

The ornamental design for a light-emitting diode, as shown and described.

DESCRIPTION

FIG. 1 is a perspective view of a light-emitting diode showing our new design;

FIG. 2 is an enlarged view of the light-emitting diode of FIG. 1;

FIG. 3 is another perspective view of the light-emitting diode;

FIG. 4 is a front elevational view of the light-emitting diode;

FIG. 5 is a rear elevational view of the light-emitting diode;

FIG. 6 is a left side view of the light-emitting diode;

FIG. 7 is a right side view of the light-emitting diode;

FIG. 8 is a top plan view of the light-emitting diode; and,

FIG. 9 is a bottom plan view of the light-emitting diode.

The broken line showing is for the purpose of illustrating environmental structure and forms no part of the claimed design.
